UNITED STATES PATENT OFFICE

CHRISTOPHER A. SCHELLENS, OF MARBLEHEAD, MASSACHUSETTS, ASSIGNEE TO C-E
ENGINEERING COMPANY, OF ENGLEWOOD, NEW JERSEY, A CORPORATION OF DELA-
WARE

PACKING FOR CENTRIFUGAL PUMPS

Original application filed January 12, 1927, Serial No. 160,539 which in turn is a division of application Serial No. 723,469, filed July 1, 1924. Again divided and this application filed March 30, 1929. Serial No. 351,901.

This invention relates to improvements in centrifugal pumps, and is particularly useful as a boiler feed water pump.

This application is a division of my co-pending application, Serial No. 160,539, filed January 12, 1927, which, in turn, is a division of my application Serial No. 723,469, filed July 1, 1924, now issued as Patent No. 1,664,488 of April 3, 1928.

10 Centrifugal pumps for feeding boilers, such as locomotive boilers for example, must be well adapted to deliver at small volumes and high pressures, and I, therefore, provide a high speed centrifugal pump having such characteristics.

15 In pumps of this character difficulties are encountered from leakage, particularly since it is necessary to maintain a sensible clearance between the pump runner and the pump casing. In this connection it is pointed out that the water, in passing through the runner, develops considerable pressure, and leaks back, and where the delivery volume is small, this leakage, which is a dead loss, 20 forms a large proportion of the delivery volume, and is, therefore, prohibitive.

The primary object of my invention is to overcome these difficulties.

25 More specifically stated, it is an object of my invention to provide very effective sealing means in pumps of the character described whereby high pressure leakage is prevented.

How the foregoing, together with such other objects and advantages as may herein-after appear, or are incident to my invention, are realized is illustrated in preferred form in the accompanying drawings, wherein—

30 Fig. 1 is a section through a pump constructed in accordance with my invention with certain of the parts appearing in elevation.

Fig. 2 is an enlarged view showing the runner partly in elevation and partly in section, and illustrating my improved sealing means in association therewith; and

Fig. 3 is a face view of a sealing ring.

In the drawings, the pump A, in general, comprises a casing 4 having a water inlet 5 to 35 the pump bowl 6, around which there is the

discharge chamber 7 having an outlet 8 to the boiler; and a runner or impeller C secured to the end of the drive shaft 9, the shaft being threaded into the face of the runner casting opposite the intake side and the runner having a hub 10 for this purpose. The shaft 9 is supported by suitable bearing means 11 and may be driven by a high speed motor, such as a high speed steam turbine motor.

It is to be observed that the shaft 9 extends only partly into the runner C from the face opposite the intake side thereof which enables me to arrange the inlet ends of the fluid passages on a small radius.

The runner C has an axial intake and a radial discharge from its periphery. It has a plurality of water passages c terminating at the entrance or intake side in a plane perpendicular to the axis of rotation, the intake ends of said passages being arranged in a circular group on a small radius around the central boss or crown 12. The walls between the passages constitute cutting blades. The runner illustrated is of the form shown in my Patent No. 1,664,488 issued April 3, 1928.

By employing such a runner having an inlet eye of small diameter, I am enabled to employ a correspondingly small diametered inlet throat or nozzle, and thus I am enabled to cut down the amount of leakage very materially.

In the drawings the nozzle or throat is indicated at 16, and it is in a sense a floating member arranged to prevent leakage because of the following provision.

The throat 16, in this instance, comprises a ring 17 having inner flanges 18 and 19 extending from opposite faces thereof. The flange 18 slidably fits in the sleeve 20 threaded into the bowl of the pump, and the ring can thus shift axially. The ring is prevented from rotating by means of the pin 21.

The body of the ring lies in the pressure space of the bowl, and since the external diameter of the flange 19 is less than the external diameter of the flange 18, the area of the face of the body of the ring toward the impeller is greater than the area of its other

face. The outer flange 22 of the ring has less depth than the flange 19.

Stated more specifically, and referring to Fig. 2, the external diameter 19a of the flange 19 is less than the external diameter 18a of the flange 18, and, therefore, the area *a* of the face of the body of the ring toward the impeller is greater than the area *b* of its other face.

10 The operation is as follows. Assuming that the pump is at rest and the flange 19 is in contact with the runner, on starting up, the ring will be subject to unbalanced pressure which will move the ring away from the runner axially. As the ring moves a gap is opened between the flange 19 and the runner, and the ratio of clearance, as between the flange 19 and the runner to that between the flange 22 and the runner, will increase, in consequence of which the pressure between the ring and the runner decreases. (The same result could be obtained by drilling holes in the flange 22, instead of making it of less depth.) Soon a point is reached where the force tending to push the ring away from the runner is balanced by the pressure on the back of the ring and the ring "stays put" at a definite clearance from the runner. By proper proportioning, this clearance can be accurately determined in advance, and I prefer to so proportion the parts as to maintain a clearance of from .001 to .002 of an inch. With this clearance, the leakage is not sufficient to impair the efficiency of the pump in an amount which would render the pump unsuitable for the use intended, while, at the same time, rapid wear is avoided, and the pump will remain in satisfactory operating condition for long periods. While I prefer to proportion flanges 18 and 19 so as to obtain a slight clearance between the ring 17 and the runner C as described above, I may so proportion these flanges as to permit the ring to touch the impeller with a light pressure between the surfaces in contact.

In further explanation of the above, let us assume that the ring 17 is touching the impeller, as shown in the drawings, and that there is clearance at 22a, under which conditions full discharge pressure will build up in the chamber D. However, since the inner flange 19 has less diameter than the flange 18, the ring will be subject to a pressure differential and move away from the impeller, immediately opening clearance between flange 19 and the impeller. This immediately reduces the pressure in chamber D, but this pressure adjusts itself so as to produce a very small clearance between the sealing ring and the impeller.

It will be noted that the inner diameter of the throat 16 corresponds to the outer diameter of the inlet eye of the impeller, and that, as the inlet eye is of small diameter, the diameter of the sealing flange 19 is also small,

which reduces very materially the area of the sealing surface, and, consequently, minimizes leakage. Were the diameter of the eye increased the leakage would be increased.

A similar automatic, pressure operated, 70 packing or sealing device 17a is provided at the other face of the runner and operates in the manner above set forth to provide the necessary clearance for the runner, but holds such clearance at a minimum so that the loss through leakage is kept within allowable limits.

80 Referring to Fig. 3, it will be seen that the face of the ring which faces the impeller has an interrupted groove 24 leaving several ribs 25 having the same depth as the flange 19 which tend to prevent cocking of the ring.

I claim:—

85 1. In a centrifugal pump, the combination of a casing, a runner, and a packing member having a leak restraining connection with one of said elements permitting of axial motion relative thereto, said member having means whereby it is held removed by a small clearance from the other element under influence of fluid pressure.

90 2. In a centrifugal pump, the combination of a casing, a runner, and a packing member having a leak restraining connection with one of said elements permitting of axial motion relative thereto, said member having a face adapted for possible contact with an adjacent face of the other element, and means effecting a pressure holding of said faces apart by a slight clearance.

95 3. In a centrifugal pump, the combination of a casing, an impeller, and a packing device for preventing high pressure leakage to the inlet side of the pump, said device comprising a floating member having a portion adapted to be pressure held removed from the impeller by a small clearance and a portion effecting such operation of the member.

100 4. In a centrifugal pump, the combination with its impeller and casing, of a floating packing member guided in the casing and operating to maintain a seal against high pressure leakage past the impeller to the suction side of the pump, said member having an inner annular rib, an outer annular rib of less depth than the inner rib and a connecting web forming a chamber having communication with high pressure fluid, the face of said inner rib being adapted to coact with a face of the impeller to form the aforesaid seal, and the face of the outer rib being arranged to be in spaced relation to a face of the impeller to form a fluid inlet to the aforesaid chamber.

105 In testimony whereof I have hereunto 125 signed my name.

CHRISTOPHER A. SCHELLEN.
